(57) **CLAIM**

The ornamental design for a cap for vial, as shown and described.

DESCRIPTION

FIG. 1 is a top perspective view of the cap for vial of the present invention;

FIG. 2 is a bottom perspective view thereof;

FIG. 3 is a right-tilted bottom perspective view thereof;

FIG. 4 is a front elevational view thereof;

FIG. 5 is a top plan view thereof;

FIG. 6 is a bottom plan view thereof;

FIG. 7 is a right side elevational view thereof, the left side elevational view being identical thereto;

FIG. 8 is a sectional view taken along line 8—8 in FIG. 4;

FIG. 9 is a sectional view taken along line 9—9 in FIG. 4;

FIG. 10 is a top perspective view thereof with cover removed; and,

FIG. 11 is a sectional view taken along line 8—8 in FIG. 4 showing the cap for vial in a state of use, fitted onto a vial with stopper.

The broken lines are for illustrative purposes only and form no part of the claimed design.
